ABSTRACT

A barb construction for a felting needle comprising a convex arcuate spur and a bottom wall extending obliquely from the base of the spur to the outer surface of the felting needle's elongated body. The bottom wall is defined by three distinct contiguous surfaces which are centered along a line parallel to the centerline of the needle's body.

FELTING NEEDLE

BACKGROUND OF THE INVENTION

The present invention relates to improvements in felting needles.

In my U.S. Pat. No. 3,307,238, a novel barb construction is disclosed which minimizes the destruction of fibers during the felting process by providing a spur having a rounded material-engaging surface. This invention improves the barb construction disclosed in the above-mentioned patent by providing a stronger barb design that permits a smoother and more positive felting action with less friction upon the fibers.

SUMMARY OF THE INVENTION

A stronger and improved barb construction for a felting needle comprising a convex arcuate spur and a bottom wall extending obliquely from the base of the spur to the outside surface of the felting needle's elongated body to define a throat for the needle. The bottom wall is formed by three distinct contiguous surfaces that are centered along a line parallel to the center line of the needle's body. The innermost surface of the bottom wall is formed as a segment-shaped fillet centered about the base of the spur face.

The innermost surface of the bottom wall has an oblique concave configuration centered about the base of the barb to reinforce the support of the barb and to provide a rounded fiber-carrying surface for improved felting action.

The intermediate surface of the bottom wall is formed by two intersecting flat surfaces which define a ridge extending parallel to the center line of the felting needle's body. This intermediate surface is the deepest portion of the bottom wall and performs the function of locating the tool on the edge of the felting needle's body to correctly align it with respect to the longitudinal axis of the body.

The outermost surface of the bottom wall extends at a diagonal angle toward the outer surface of the needle body and is formed as a convex configuration centered on a line parallel to the centerline of the needle body.

DESCRIPTION OF DRAWING

For a better understanding of this invention, reference may be made to the accompanying drawing, in which:

FIG. 1 is an elevational view of one form of felting needle of my present invention fabricated as described herein below;

FIG. 2 is a greatly enlarged perspective view of a portion of the body of the needle of FIG. 1 showing the improved barb construction of the present invention;

FIG. 3 is a side elevational view of the same portion of the needle body shown in FIG. 2;

FIG. 4 is a plan view of the same portion of the needle body as illustrated in FIG. 2;

FIG. 5 is a cross-sectional view taken along the line 5-5 of FIG. 3; and

FIG. 6 is a sectional view taken along the line 6-6 of FIG. 3.

DESCRIPTION OF PREFERRED EMBODIMENT

Referring now to FIGS. 1 and 2 of the drawing, I have shown a felting needle 10 constructed in accordance with my invention which comprises a body portion 12 and a shank portion 14. The lower end of the body portion 12 is pointed as at 16 to facilitate penetration of fibrous material to be compacted in a known and conventional manner. The upper end portion of the needle may be bent substantially at right angles to the shank portion 14 to provide a securing element or ear 18 for clamping between a base member and a clamping member of a conventional needle plate. As is well known, such a needle plate is adapted to support a plurality of felting needles, such as shown in FIG. 1, which in reciprocation of the plate in the felting machine effects the interlacing and compacting of loose fibrous materials.

It is preferable in practicing my present invention to provide a felting needle having a salient angled body portion, that is a body portion having intersecting surfaces providing an edge, such as shown at 20 in FIG. 2, of sufficient longitudinal extent

5 for a spur 22 and associated recess or throat 24. Typically for such purpose the body portion 12 may be of polygonal cross section such as of conventional triangular cross section currently employed in the art and as illustrated in the fragmentary portion of the body 12 of the needle shown in FIG. 2. A body portion of triangular cross section provides three edges at which spurs may be formed and in practicing my invention, a single spur and recess may be formed in one or more such edges or a plurality of spurs may be provided in the edges as desired.

15 As shown in FIG. 2, a portion of the material of the body of the needle in the corner edge 20 is displaced to form the recess 24 and such displaced material is shaped into a barb above the recess.

20 The recess or throat 24 and the spur 22 are formed in the edge 20 by a spur-forming tool, such as is described and shown in my prior U.S. Pat. No. 3,307,238. In the application of such a tool to the edge 20 of the body of the felting needle, the spur 22 is formed to extend laterally outwardly of the body portion with the fiber or material-engaging surface projecting downwardly or toward the pointed end of the needle. The spur 22 is defined by downwardly converging lateral side surfaces

25 25 and joined by a convex material engaging surface 26.

The bottom wall 28 of recess 24 is defined by three distinct contiguous surfaces 30, 32 and 34. Innermost surface 30 has a concave shape formed as an oblique circuitous configuration centered about the base of the spur 22. This oblique or beveled surface serves as a reinforcing means for the spur 22 by taking the form of a segment-shaped fillet joining the bottom wall 28 and the fiber-engaging surface 26. Also by virtue of its oblique concave shape, innermost surface 30 provides a further rounded fiber-carrying surface for improving the felting action.

Intermediate surface 32 of bottom wall 28 comprises two intersecting plane surfaces 36 and 38 extending at an obtuse angle from ridge 40 which is parallel to the longitudinal center line of the needle body 12. The configuration of this intermediate surface is important in that its formation in the needle body 12 results in the accurate alignment of the barb-forming tool on the edge 20. Because this intermediate surface is the

40 deepest portion of the bottom wall 28, the grooved portion of the barbing tool which forms its surface will be the first part of the barbing tool to come in contact with the edge 20 of the needle body and consequently this intermediate surface 32 can serve to function as a surface guiding means for positioning the tool with respect to the needle body. It has been found that very satisfactory results are obtained when the planes 36, 38 are separated by an obtuse angle of approximately 120°. It will be noted that the center line of the innermost and outermost surfaces 30, 34 are in alignment with the ridge 40 of the intermediate surface 32.

45 Because of this relationship, it is possible to accurately form the barb 22 and associated throat 24 to be parallel to the center line of the needle body 12. The outermost surface 34 of the bottom wall 28 has a convex configuration extending at a diagonal angle downwardly of the body 12 and serves to shed the fibers as are needed. The total length of bottom wall 28 can be selectively varied by changing the angle between the outermost surface 34 and the outer surface of body portion 12 to thereby selectively change the throat opening 24. This selective feature permits control over the admittance of fiber into the throat 24 to determine the number of fibers needled per stroke.

50 As is clearly depicted in FIG. 4, the spur 22 and its associated throat 24 formed in accordance with this invention provide a continuous series of surfaces centered on a line parallel to the center line of the needle body 12. One beneficial result of this arrangement is to distribute the point of maximum barbing tool penetration of the needle body equally over an area to avoid concentrated stresses in the steel grain structure and thereby improve barb strength.

55 70 75

A significant structural feature of the present invention is the provision of a rounded beveled surface centered about the base of the spur, such as surface 30, which reinforces the barb or spur and eliminates any shearing or chopping effects at the base of the spur when engaging the fibers. A further structural feature resides in the inclusion of a surface having two intersecting planes to define a distinct ridge which insures that the barb-forming tool is correctly aligned on the needle edge.

While I have shown and described what I considered to be a preferred embodiment of the felting needle of the present invention, it will be understood that various modifications may be made therein without departing from the spirit and scope of the invention.

I claim:

1. A felting needle comprising a body portion, a recess in said body portion, a spur at said recess, said recess being defined by a bottom wall extending from the base of said spur to the outer surface of said body portion, said bottom wall having surface guiding means to cause the correct alignment of the barb-forming tool on one of the edges of said body portion such that said spur and recess will be formed on a line parallel to the centerline of said body portion. 15

2. A felting needle as defined in claim 1, wherein said surface guiding means comprises a ridge defined by two intersecting plane surfaces extending outwardly of said recess, said ridge being parallel to said centerline of said body portion. 20 25

3. A felting needle as defined in claim 1, wherein said bottom wall includes a concave surface extending obliquely from the face of said spur centered about said base.

4. A felting needle comprising a body portion, a recess in said body portion and a spur at said recess having a convex material-engaging surface at its lower end formed between downwardly converging lateral surfaces of the spur, said recess being defined by three distinct contiguous surfaces extending from said lower end of said spur to the outer surface of said body portion, the innermost of said surfaces having a concave configuration extending obliquely from and centered about said convex material-engaging surface of said spur. 10

5. A felting needle as defined in claim 4, wherein the intermediate of said three surfaces is shaped to cause the correct alignment of the barb-forming tool on one of the edges of said body portion such that said spur and said recess will be formed on a line parallel to the centerline of said body portion.

6. A felting needle as defined in claim 5, wherein said intermediate surface comprises two outwardly converging plane surfaces which intersect to define a ridge parallel to the centerline of said body portion. 20

7. A felting needle as defined in claim 4, wherein the outermost of said three surfaces has a convex shape and extends at a diagonal angle to the outer surface of said body portion. 25
